Devolson Reed
By his Attorney F. W. Ritter Jr.

UNITED STATES PATENT OFFICE.

DEVOLSON REED, OF RANDOLPH, NEW YORK, ASSIGNOR OF ONE-HALF TO
CHARLES C. PARSONS, OF SAME PLACE.

CLOTHES-DRIER.

SPECIFICATION forming part of Letters Patent No. 430,970, dated June 24, 1890.

Application filed October 21, 1889. Serial No. 327,657. (No model.)

To all whom it may concern:

Be it known that I, DEVOLSON REED, a citizen of the United States, residing at Randolph, in the county of Cattaraugus, in the State of New York, have invented certain new and useful Improvements in Clothes-Driers; and I hereby declare the following to be a full, clear, and exact description of the same, reference being had to the accompanying drawings, in which—

Figure 1 is a perspective view of a folding clothes-drier embodying my invention spread or open as when in use. Fig. 2 is a perspective view of said clothes-drier closed or folded as for storage or when not in use.

Like symbols refer to like parts wherever they occur.

My invention relates to the construction of that class of articles termed "clothes-driers" or "clothes-bars," commonly employed indoors for drying and airing clothes, and has for its object to obtain a simple, strong, light, and convenient form of folding portable clothes-drier.

The main feature of my invention consists in the combination, in a clothes-drier, of a series of radially-arranged tapering frame-pieces, and a series of encircling hoop-like clothes bars or supports formed of rigid material, whereby a barrel-like structure of great lightness, strength, and simplicity is obtained.

Subordinate features embrace the combination, with a series of radially-arranged folding frame-pieces, of a series of half-hoops or bail-like clothes-bars, whereby compactness, strength, and lightness are obtained.

There are other minor points of invention, all as will hereinafter more fully appear.

I will now proceed to describe my invention more specifically, so that others may apply the same.

In the drawings, 1 indicates a central block or base-piece provided with supports 2, two of which supports, if desired, may be placed opposite each other or in the same plane and rigidly secured to the base-block, while for convenience in packing the other supports are preferably hinged to the block or base-piece 1, as at 3, so as to fold against the two fixed supports.

Journalized on or in the base-piece 1 is a ver-

tical post 4, forming a suitable rotary support for the frame-pieces 5, any number of which may be used, and all of which are attached to or supported by the central post 4. 55 I preferably employ four, as shown, and in such case two of said frame-pieces 5 may be rigidly attached to or framed on the central post 4, while the remaining frame-pieces 5 may be pivoted or hinged to the post, as at 6, 60 so as to fold against the fixed frame-pieces to facilitate storing of the drier when not in use.

77 indicate the bar-supports or clothes-supports, and which, singly considered, are in the form of bails pivoted on two of the 65 frame-pieces, preferably the two opposite and fixed frame-pieces 5^a 5^b, by means of ears 8. These bail-like supports or curved support-bars 77 are, however, preferably arranged in pairs, or each two in the same 70 plane, as shown, to form hoop-like supports for the frame-pieces 5, and said frame-pieces are preferably formed with sloping outer faces, as shown, so that when the frames 5 are spread or extended the hoop-like clothes-bars 7 will bind them or force them toward the post as a common center, thus proportionately increasing the firmness and rigidity of the frame accordingly as the load thereon increases. 75

The hoops or bails 77, as shown, may be of galvanized wire, which will be of sufficient strength where a folding frame with rigid center post 4 is employed in the construction, and is the most desirable material in a folding drier; but in case of a non-folding frame, or in case of a "knockdown" frame, where the frames are to be held together by the hoops or bails, it will be found desirable to use galvanized hoop-iron or more rigid material. 80

It may sometimes be desirable to suspend the folding drier, and for this purpose a loop or ring 9 may be applied to the top of the central post 4. 85

When in use, the several frame-pieces 5 will be arranged radially with relation to the central post 4, as shown in Fig. 1, and will support (as well as be supported by) the hoop-like encircling bails or bar-supports 77. 100 When not in use, the movable or hinged supports and frame-pieces may be folded against

the fixed supports and frame-pieces 5, as shown in Fig. 2, which will permit the pivoted half-hoops or bail-support bars 77 to drop down or be folded flat against the frames, so that the devices may be stored in a small space.

I have herein described some of the supports 2 and frame-pieces 5 as hinged to the base-block 1 and the post 4. I have also described the post 4 as journaled in the base-block 1 and the half-loop or bail-supports 7 as pivoted on the fixed frame-bars 5, which is the preferred construction, and embraces all the desirable features in a folding clothes-drier embodying my complete invention; but it is evident that a clothes-drier composed of a series of radially-arranged tapering frames and a series of encircling hoops, said frames being either detachable or framed together, will embody the main feature of my invention, will secure the lightness, simplicity, and strength which is characteristic of my invention, and will answer all requirements where a folding clothes-drier is not desired. In case the frames 5 are separable the hoop-like supports 7 will bind them firmly together, and a knockdown drier may be cheaply formed.

Having thus described my invention, what I claim, and desire to secure by Letters Patent, is—

1. In a clothes-drier, the combination of a series of radially-arranged tapering frame-pieces and encircling hoop-like supports formed of rigid material, substantially as and for the purposes specified. 30

2. In a clothes-drier, the combination of a series of radially-arranged tapering frame-pieces and a series of encircling bails or pivoted half-hoops, substantially as and for the purposes specified. 35

3. In a clothes-drier, the combination of a series of radially-arranged frames, some of which are hinged to fold against the others, and a series of encircling half-hoops or bails pivoted on opposite frame-pieces, substantially as and for the purposes specified. 40

In testimony whereof I affix my signature, in presence of two witnesses, this 17th day of October, 1889.

DEVOLSON REED.
